[57] CLAIM

The ornamental design for roof tile or similar article, as
shown and described.

DESCRIPTION

FIG. 1 is a front elevational view of a roof tile or similar
article showing my new design;

FIG. 2 is a top plan view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a cross-sectional view taken substantially
along line 7—7 of FIG. 2;

FIG. 8 is a cross-sectional view taken substantially
along line 8—8 of FIG. 2;

FIG. 9 is a cross-sectional view taken substantially
along line 9—9 of FIG. 2; and

FIG. 10 is a cross-sectional view taken along line
10—10 of FIG. 2.

FIG. 4

FIG. 5
